UNITED STATES PATENT OFFICE.

EMIL VON LEESEN, OF BERLIN, GERMANY.

PNEUMATIC HAMMER.

Application filed July 11, 1921. Serial No. 483,928.

To all whom it may concern:

Be it known that I, EMIL VON LEESEN, a citizen of Germany, residing at Berlin, Germany, have invented certain new and useful Improvements in Pneumatic Hammers, of which the following is a specification.

This invention relates in general to pneumatic hammers, more especially to controlling devices or gear for hammers of this kind having separate cylinders for the air pump and the tup piston. A feature of the novel controlling device according to the invention is that a single valve is used for connecting the lower and upper ends of the tup cylinder to the lower and upper ends of the pump cylinder or to the atmosphere. The valve used is preferably one of the rotary type with a middle chamber arranged to act as a compression chamber.

By using a single valve or member for controlling the air passages between the cylinders of the pump and hammer the leaks are reduced to the utmost and consequently the power consumed is lessened. Besides, the costs of producing the machine are diminished and its reliability of operation is enhanced.

Another advantage of the invention is that with the single controlling member or valve it is possible to use the hammer in all the different ways, or in other words, to execute all the different kinds of strokes that hitherto could only be attained with the aid of at least two main valves and auxiliary valves.

The invention is illustrated in the drawing in which—

Fig. 1 is a vertical section through the hammer,

Fig. 2 is a longitudinal section through the guide bushing of the rotary valve,

Fig. 3 is a view of a valve with an internal auxiliary back pressure valve,

Fig. 4 is a view of a valve with two internal auxiliary back pressure valves,

Fig. 5 is a cross section of the rotary valve and the passages or ports controlled thereby taken on the line 5—5 of Fig. 2,

Fig. 6 is a cross section of the valve and ports taken on the line 6—6 of Fig. 2,

Fig. 7 is a cross section of the valve and ports on the line 7—7 of Fig. 2,

Fig. 8 is a section of the cylinders and the valve on the line 8—8 of Fig. 10,

Fig. 9 is a longitudinal section of the valve on the line 9—9 of Fig. 8 and

Fig. 10 is an elevation of a pneumatic hammer.

Fig. 11 is a section on the line 11—11, Fig. 9.

Fig. 12 is a section on the line 12—12, Fig. 9.

The rotary valve *a*, (Figs. 1 to 7) which is common to the upper and lower cylinder spaces, has two main ports *b* and *c*. Through the passages *f* and *g* the port *b* establishes connections between the cylinder space beneath the under side *d* of pump piston and the cylinder space beneath the under side *e* of the piston connected to the tup, and through the passages *k* and *l* the port *c* establishes connections between the upper space *h* of the cylinder of the pump and the upper space *i* of the tup piston cylinder. The main ports *b* and *c*, as shown in Fig. 3, are respectively arranged near opposite ends of the rotary valve. The middle portion of the valve *a* has a hollow space or chamber *m* which is either connected to an end port *b* by a single back pressure valve *n* that opens from *b* to *m* as shown in Fig. 3, or which, as shown in Fig. 4, may be connected to the two end ports *b* and *c* by two back pressure valves *n* and *o* that open into *m*. The said chamber *m* has a lateral port *p* which, according to the position of the valve *a*, establishes a connection from the chamber *m* either to the lower space *e* of the tup piston cylinder through the passage *f*, or to the upper space *i* of this cylinder through the passage *k*. The bushing surrounding the rotary valve *a*, and firmly pressed into the frame of the hammer, is only provided for the purpose of enabling the inlets into the various passages *f*, *g* etc. to be accurately cut, the passages *f*, *g*, *k* and *l* themselves consisting merely of hollow spaces formed by cores when casting the body of the hammer.

The valve *a* is controlled either by the handle *r*, or by a foot lever *s* acting through the connecting rods *t*, *u*, *v*.

The mode of operation of a hammer controlled in this way will be understood from Figs. 1, 5, 6 and 7. Fig. 5 is a vertical section through the port *b* of the rotary valve and the adjoining passages *f* and *g*, Fig. 6 a vertical section through the middle chamber *m* of the valve and the adjoining passages *f* and *k*, and Fig. 7 a vertical section

through the port *c* of the valve and the adjoining passages *k* and *l*.

When the rotary valve is in the position shown in Figs. 5, 6 and 7 the tup is kept suspended in its highest position. Since the passage *f* (Fig. 5) leading to the lower tup cylinder space is closed, the lower side *d* of the pump piston will press air through the back pressure valve *n* into the pressure chamber *m* (Fig. 6) and thence through the opening *p* into the passage *f* and the lower tup cylinder space *e* (Fig. 1) thus driving the tup piston upward. At the same time the upper tup cylinder space *i* will be connected through the passage *k* (Fig. 7), a notch *x* in the valve *a*, and an outlet *y* to the atmosphere, so that for a while no resistance will be offered to the tup piston *w* by the medium in the space above it. But shortly before the tup piston reaches its topmost position its upper edge closes the mouth of the passage *k* leading into the cylinder so that an air cushion is formed which resists the further upward movement of the tup piston.

If the rotary valve is now turned by the means of the handle *r* or the pedal *s* in the direction indicated by the arrows a direct connection through the port *b* of the valve *a* (Fig. 5) will first be established between the pump cylinder space *d* and the lower tup cylinder space *e*, this connection including the passages *g* and *f*. The suctional and pressure effects produced in the lower space of the pump cylinder will cause the tup to execute gentle up and down strokes so that very gentle blows of the tup will result. If the rotary valve is turned further around in the direction of the arrows a direct connection through the port *c* (Fig. 7) will also be established between the top space *H* of the pump cylinder and the top space *i* of the top cylinder via the passages *k* and *l* and consequently the blows of the tup will gradually become more violent.

When the rotary valve is turned completely round the passages between the channels *f* and *g*, and *k* and *l*, leading through *b* and *c* respectively, will be opened to their widest extent, i. e. the connections between the upper and lower cylinder spaces will be most efficient, so that the tup will execute its most violent blows.

If the pedal *s* or the handle *r* is now released the valve *a* will be immediately restored by the weight *Q* attached to the lever *t* to the position in which it causes the tup to be raised and the tup will fly into its topmost position in which it will be kept suspended.

If desired the tup may be lowered onto the work and caused to remain thereon whilst exerting constant pressure. To this end the handle *r* is turned in the direction opposite to that indicated by the arrows.

When turned in this position the connection between the port *b* of the valve *a* (Fig. 5) and the lower tup cylinder space *e* is cut off. The lower space *d* of the pump cylinder operates through the back pressure valve *n* with the pressure space *m* whose port *p* registers with the passage *k* leading to the upper tup cylinder space *i* so that the tup piston is forced down by compressed air from above. At the same time the lower tup cylinder space *e* will be connected through the passage *f*, (Fig. 5), the notch *P* in the rotary valve and the port *H* to the atmosphere, and the connection extending from the passage through the notch *x* to *k* the port *y* (Fig. 7), which leads into the atmosphere will be closed. On the other hand the upper space *h* of the pump cylinder will still be connected to the atmosphere through the notch *E* and the ports *l* and *y*.

Finally, if the tup is to be caused to execute single strokes at any desired speed independently of the number of strokes carried out by the pump it is only necessary to shift the handle *r* to and fro at the desired speed from the position in which it causes the tup to be lowered, and kept constantly pressing down on the work, into the position in which it causes the tup to be kept suspended in its topmost position.

Fig. 4 shows a modification of the rotary valve for hammers for swaging work. When this form of valve is turned into the position in which it causes the tup to remain suspended in its topmost position, or in which it causes the tup to constantly press down on the work, the upper and lower pump cylinder spaces are both connected through the two back pressure valves *n* and *o* to the pressure chamber *m*, and a higher and more uniform pressure is thus obtained. The cross section of the valve *a* on the line 7—7, Fig. 2 is then made similar in shape to the section on the line 5—5, Fig. 2 and the notch *P* in the exterior of the rotary valve is omitted.

In the modification shown in Figs. 8 and 9 the rotary valve is subdivided and the individual parts are arranged to be adjusted with respect to each other.

The interior of the one half *R* of the valve is a chamber *R'* with ports adapted to effect connections between the lower spaces of the cylinders. The other half of the valve *S* comprises a chamber *S'* with ports adapted to effect connections between the upper spaces of the cylinders. Between the two halves *R* and *S* of the valve which are arranged in a common bore there is a pressure chamber *M'* adapted to be filled with air that passes in from the chambers *R'* and *S'* through the back pressure valves *N'* and *O'*. The compressed air from the pressure space *M'* may be conducted through a channel *Z'* in the valve member *R* into the air

passage F' and the lower space E' in the tup cylinder. By this means the tup is kept in its topmost position.

By turning the valve in a suitable manner 5 a similar channel in the valve member S is brought into a position in which compressed air passes from the pressure chamber M' through the air passage k into the top space in the tup cylinder. By this means the tup 10 is caused to press steadily down onto the anvil. By arranging the one half R of the valve on a cone K of the common shaft L and the other half S on an elastic key m the two said valves are made adjustable with respect to each other.

The elastic connection by means of the shaft obviates the possibility of the valves 20 becoming stuck in the bore through unequal heating which is very liable to occur in the case of valves accurately fitted into their holes by grinding.

I claim:—

1. In a pneumatic hammer, a tup piston, a pump piston, separate cylinders for the said 25 pistons, primary passages for interconnecting the cylinder spaces above the said pistons, secondary passages for interconnecting the cylinder spaces beneath the said pistons, a port for connecting the tup cylinder to the atmosphere; a single oscillatory valve controlling all of the said passages and the said port; means for operating said valve, and means whereby when the valve operating means is released the valve is positioned 30 to elevate the tup piston.

2. In a pneumatic hammer, a tup piston, a pump piston, separate cylinders for the said 40 pistons, primary passages for interconnecting the cylinder spaces above the said pistons, secondary passages for interconnecting the cylinder spaces beneath the said pistons, a port for connecting the tup cylinder to the atmosphere; a single rotary valve with ports at its two ends and a chamber at its middle portion, the said rotary valve being adapted to control all of the 45 said passages and the said port; means for operating said valve, and means whereby when the valve operating means is released the valve is positioned to elevate the tup piston.

3. In a pneumatic hammer, a tup piston, a pump piston, separate cylinders for the said 55 pistons, primary passages for interconnecting the cylinder spaces above the said pistons, secondary passages for interconnecting the cylinder spaces beneath the said pistons, a port for connecting the tup cylinder to the atmosphere; a single rotary valve having ports at its two ends, a pressure chamber at its middle portion, and a back pressure valve between one of its ports and its 60 pressure chamber, said rotary valve being adapted to control all of the said passages and the said port; means for operating said

valve, and means whereby when the valve operating means is released the valve is positioned to elevate the tup piston.

4. In a pneumatic hammer, a tup piston, a pump piston, separate cylinders for the 70 said pistons, primary passages for interconnecting the cylinder spaces above the said pistons, secondary passages for interconnecting the cylinder spaces beneath the said pistons, a port for connecting the tup cylinder to the atmosphere; and a single rotary valve comprising, two port chambers which are adjustable with respect to each other, the valve being adapted to control the said 75 passages and the said port.

5. In a pneumatic hammer, a tup piston, a pump piston, separate cylinders for the said pistons, primary passages for interconnecting the cylinder spaces above the said pistons, secondary passages for interconnecting the cylinder spaces beneath the said pistons, a port for connecting the tup cylinder to the atmosphere; and a single rotary valve comprising, two port chambers, a common shaft 85 connecting the two chambers, the two chambers being adjustable with respect to each other, and the one chamber cooperating with the upper cylinder spaces, whilst the other cooperates with the lower cylinder 90 spaces, the said valve being adapted to control the said passages and the said port.

6. In a pneumatic hammer, a frame, a tup piston, a pump piston, separate cylinders for the said pistons, primary passages for interconnecting the cylinder spaces above the said pistons, secondary passages for interconnecting the cylinder spaces beneath the said pistons, a port for connecting the tup cylinder to the atmosphere, a bore in the 100 said frame; and a single rotary valve arranged in the said bore and comprising, two port chambers, a common shaft for the two port chambers, these chambers being mounted on the shaft in the said bore at a distance 105 from each other so that a middle chamber is formed in the said bore, ring-shaped back pressure valves for connecting the port chambers with the said middle chamber, the one back pressure valve cooperating with the said primary passages, whereby the tup piston is lowered, and the other back pressure valve cooperating with the said secondary 110 passages, whereby the tup piston is raised.

7. In a pneumatic hammer, a frame, a tup piston, a pump piston, separate cylinders for the said pistons, primary passages for interconnecting the cylinder spaces above the said pistons, secondary passages for interconnecting the cylinder spaces beneath the said pistons, a port for connecting the tup cylinder to the atmosphere, a bore in the 120 said frame; and a single rotary valve arranged in the said bore and comprising, two port chambers, a common shaft for the two 125 port chambers, a common shaft for the two 130

port chambers, the shaft having a conical portion at the middle and two threaded portions near its ends, a nut on one of the said threaded portions for fixing one of the said port chambers on the said conical portion, a second nut and a key on the common shaft for fixing the other port chamber, both chambers being mounted on the shaft in the said bore at a distance from each other so that a middle chamber is formed in the said bore, ring-shaped back pressure valves for connecting the port chambers with the said

middle chamber, the one back pressure valve cooperating with the said primary passages, whereby the top piston is lowered, and the other back pressure valve cooperating with the said secondary passages, whereby the tup piston is raised. 15

In testimony whereof I have signed this specification in the presence of two witnesses.

EMIL VON LEESEN.
